UNITED STATES PATENT OFFICE.

GEORGE SCHMITT, OF GLENMONT, NEW YORK.

DIRIGIBLE HEADLIGHT.

1,050,237.

Specification of Letters Patent. Patented Jan. 14, 1913.

Application filed November 27, 1911. Serial No. 662,588.

To all whom it may concern:

Be it known that I, GEORGE SCHMITT, a citizen of the United States of America, residing at Glenmont, in the county of Albany and State of New York, have invented certain new and useful Improvements in Dirigible Headlights, of which the following is a specification.

My invention relates to dirigible head-lights, and the object of my invention is to provide a headlight adapted to be placed on an automobile and to be moved simultaneously with the change in direction of the machine, governed by the direction of movement of the wheels, or which may be held rigidly in position when desired; together with such elements and combinations as are hereinafter more particularly set forth and claimed.

I accomplish these objects by means of the mechanism illustrated in the accompanying drawings, in which:

Figure 1 is a side elevation partly in section, showing the lamp post out of gear. Fig. 2 is a front elevation partly in section. Fig. 3 is a plan of the gear. Fig. 4 shows an elevation of plain lamp post and standard on opposite side of car which is controlled by the movements of the lamp post shown in Fig. 1. Fig. 5 is a plan of the lever disk, 8. Fig. 6 is a plan of the plate, 9. Fig. 7 is a plan of the link, 10. Fig. 8 is a plan of link, V'. Fig. 9 is a plan showing the position of the locking device when the lamp is held rigidly in position. Fig. 10 is a plan showing the position of the locking device when the rigid connecting device has been broken. Fig. 11 is a plan showing the position of the locking device when the lamp post is in gear with the wheels. Fig. 12 is a general view, with parts omitted, showing the position of the lamps on each side of the machine connected together and adapted to be moved simultaneously with the wheels.

Similar letters refer to similar parts throughout the several views.

The lamp post, A, is mounted within a standard, B, secured by bolts passing through suitable ears, C, to the chassis, D, of the machine. Attached to the lamp post, A, is a plate, E, separated from the top of

the standard, B, by balls, F, making an anti-friction bearing, but provided with a flange, b, which projects over the end of the standard, B, and prevents dust from entering between the plate and upper edge of the standard. The plate, E, is provided with an arm, G, to which is attached one end of the rod, H, which extends across the machine and is there connected with a similar arm, h, on the plate, e. The plate, E, has a recess, J, extending from its underside into the plate, adapted to receive a locking bolt, K, which bolt when inserted will prevent a movement of the plate, E, and therefore of the lamp post, A, to which it is attached.

In the standard, B, I mount a crank shaft, I, provided with two offsets, M, N. To the crank shaft, L, at the offset, M, I attach the link, 10, secured to the bolt, K. At the offset, N, to the crank shaft, L, I attach the link, 11, connecting with the stud, O. On the squared end of the crank shaft, L, extending beyond the standard, B, I place the lever disk, 8, which has a square opening therethrough for the reception of the similarly formed end of the crank shaft, but permitting a reciprocatory motion of the lever disk on the crank shaft. The lever disk, 8, provided with a lever arm, 12, rests against the plate, 9, through which the crank shaft, L, passes and which is preferably provided with a collar, 13, inserted in the opening of the standard, B, as shown in Fig. 1. On the face of the lever disk, 8, I place a projecting rib, 14, extending transversely thereof and adapted to engage in a corresponding slot, 15, in the plate, 9. Resting against the disk, 8, and against a nut, 16, on the end of the crank shaft, L, is a spiral spring, 17, the resiliency of which tends to keep the disk, 8, in engagement with the plate, 9. The two lock nuts, A', on the end of lamp post, A, are for the purpose of taking up all lost motion due to wear.

The stud, O, is provided with a groove, P, registering with the groove, P', in the gear, R, into which groove a pin, p, is fitted to insure the movement of gear, R, with that of the stud, O. Through the stud, O, I place a pin, T, against which one end of the springs, t, rest and whose force is expended

in endeavoring to lift the stud, O, to balance the mechanism, as shown in Fig. 2. The springs, t, may be mounted on a suitable pin, t', or in any suitable manner.

5 The gear, R, is preferably constructed as shown in Fig. 3, in which a horizontal disk portion, r, is provided with the raised, rounded portions, r', r² and r³, spaced equally from each other and raised above 10 the disk portion, r. On the lamp post, A, is a gear in the form of a disk, a, provided with projecting arms, a', a², a³ and a⁴, so arranged in reference to the projections, r', r² and r³, on the gear, R, that the points 15 will engage the projections readily without jar or hesitation. The arms, a', a², being preferably pointed and formed to make connection smoothly between them and the projections and without any lost motion.

20 Attached to the gear, R, is a stud, V, to which is secured a link, V' attached to the rod, W, which has at its end a coupling, X, which is secured to the wheel knuckle, not shown. By this arrangement of the coupling, rod, link, stud, and gear the direction 25 of the movement of the wheel will be communicated to the lamp post which will be rotated thereby.

When the position of the lever disk, 8, 30 and lever arm, 12, attached thereto is such that the bolt, K, is inserted into the recess, J, in the plate, E, the stud, O, will be so acted upon by the link, 11, and offset, N, that the gear, R, will be away from the gear, 35 a, and as a consequence the lamp post and lamp secured thereto will be held rigidly in position in connection with the chassis of the machine. When the lever arm, 12, is moved to the position indicated by the parts 40 shown in Fig. 10, the bolt, K, will be withdrawn from the plate, E, but the stud, O, has not yet been raised sufficiently to bring the gear in connection with that on the lamp post. A further movement of the lever arm, 45 12, will place the locking parts in the position shown in Fig. 11, in which the bolt, K, is out of connection with the plate, E, and the stud, O, has brought the gear, R, in register with the gear, a. In this position the 50 lamp post, A, is moved by the changed direction of the movement of the wheels of the car. When in this position the rib, 14, on the lever disk, 8, is in register with the groove, 15, on the plate, 9, and the lever disk, 8, is held in connection with the plate, 9, by the spring, 17, thereby preventing an 55 unintentional movement of the lever arm, 12.

When the operator desires to break connection between the gears, he simply moves 60 the lever arm, 12, in a direction opposite to what he does in making the connection and the gear, R, will be thrown out of engagement with the gear, a, after which a further movement of the lever arm will cause

the bolt, K, to enter the recess, J, and lock 65 the plate, E.

By my arrangement I am able to have the lamps so placed that they will cause a light to be thrown in the direction in which the machine is going, even when making a 70 curve, and as soon as the wheels are turned, which of course is very desirable especially when traveling on a comparatively unknown road. I can also by my invention disconnect the lamp post from the wheels so that in 75 the daytime the lamps will not be subjected to this movement.

The bent rods, 20, may be used for supporting the lamps (not shown) on the plates, E and e.

This application differs from my application filed December 28th, 1910, and which was allowed August 18th, 1911, among other things in that I have provided here a step by step rotatable means for locking the lamp 85 post and for breaking engagement with the gear connecting the lamp post with the wheel knuckle.

What I claim as my invention and desire to secure by Letters Patent, is:

90

1. In a dirigible headlight, the combination of a lamp post; a standard in which the lamp post rotates; a gear on said lamp post; a plate attached to said lamp post; ball bearings between said plate and the upper portion of said standard; a rod carrying a gear adapted to mesh with the gear on said lamp post; step by step rotatable means for locking said plate and breaking engagement with the gear on the rod and 100 that on the lamp post and conversely.

95

2. A dirigible headlight comprising a lamp post; means for locking said lamp post rigidly in position; a gear attached to said lamp post; a rod; a gear attached to said 105 rod; means for connecting said rod with the wheel knuckle; means for step by step bringing said two gears into engagement and unlocking said lamp post.

105

3. A dirigible headlight comprising a 110 lamp post; means for mounting said lamp post so that it may be rotated; a gear carried by said lamp post; a plate attached to said lamp post; a rod; a gear connected therewith; means connecting said rod to the 115 wheel knuckle; means for locking or unlocking said plate and by a separate, independent, progressive movement disconnecting the two said mentioned gears or making connection between them, substantially as 120 described.

115

4. A dirigible headlight comprising a lamp post; a standard in which the same is mounted; a gear attached to the said lamp post; a plate attached thereto; ball bearings 125 between said plate and said standard; a crank shaft; means operated by said crank shaft for locking said plate; a gear; a rod

to which it is attached; means for bringing said last mentioned gear in connection with the gear on said lamp post by the operation of said crank shaft; said crank shaft and connections with said locking device and gear so arranged that by a partial rotation of the crank shaft said plate will become unlocked and by a further rotation in the

same direction said gears will be brought into mesh, substantially as described. 10

In testimony whereof I have affixed my signature in presence of two witnesses.

GEORGE SCHMITT.
